TOY SAVINGS BANK

Sherman W. Griselle, Chicago, Ill.

Application November 23, 1953, Serial No. 27,715

Term of patent 7 years

(Cl. D34—11)

To all whom it may concern:

Be it known that I, Sherman W. Griselle, a citizen of the United States, residing at Chicago, county of Cook, and State of Illinois, have invented a new, original, and ornamental Design for a Toy Savings Bank, of which the following is a specification, reference being had to the accompanying drawing, forming a part thereof, in which:

Fig. 1 is a front face view of a toy savings bank showing my new design;

Fig. 2 is a rear face view thereof;

Fig. 3 is a bottom edge view thereof; and

Fig. 4 is a side edge view thereof.

The broken lines indicate stitching.

I claim:

The ornamental design for a toy savings bank, as shown and described.
